ATTORNEY

UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 10, 1926. Serial No. 87,389.

This invention relates to feeler mechanisms for looms whereby when the filling becomes substantially exhausted in the shuttle the operative condition of the loom will be changed; such, for instances, as replenishing the filling.

Feeler mechanisms of the so-called intermittent type seek to prevent injury to the filling by the recurring contacts of the feeler therewith on detecting beats, and various constructions have been devised to this end. The present invention is directed to improvements in the intermittent type of feeler mechanisms, and has for one of its objects the simplification of the feeler mechanism and its disposition with respect to the loom parts whereby the train of mechanism for periodically freeing the feeler shall in no way interfere with the free access to the loom parts by the weaver or loom attendant.

In accordance with the present invention the feeler is held in an inoperative position during its periods of inactivity, and is freed at intervals that it may move to feeling position and again be returned to its inoperative position should it detect a working supply of filling in the shuttle, but should the feeler detect a near approach to substantial exhaustion of the filling, it will remain in operative position and effect replenishment of filling when that in the shuttle is substantially exhausted. The controlling means for thus freeing the feeler at intervals during weaving is associated with the cam follower and comprises a periodically active trip mechanism mounted on the cam follower, or a part movable therewith, to free the feeler to the performance of its feeling function.

The invention and new combination of parts will best be made clear from the following description and accompanying drawings of one good form thereof, wherein the means for controlling the periods of activity of the feeler are actuated from the lower cam shaft which has a one-to-two relative movement with the crank shaft. More specifically stated, the mechanism for controlling the periods of activity of the follower are mounted for bodily movement with the cam follower, or a part movable therewith.

In the drawings Fig. 1 is a perspective view at the feeler side of a loom having the present invention associated therewith, some

of the parts being broken away for clearness of illustration;

Fig. 2 is an enlarged side elevation of the trip mechanism or step-by-step device mounted upon the cam follower, the cover plate being removed;

Fig. 3 is a front edge view of the step-by-step mechanism detailed;

Fig. 4 is a detail showing one means for actuating the cam follower.

The feeler mechanism in the present instance is associated with means for effecting replenishment of filling when that in the active shuttle has become substantially exhausted, but the replenishing mechanism and details thereof are not herein shown and described because such details form no essential part of the present invention and are now well understood by those skilled in the art.

The loom frame 1 may be of usual construction, and from the end of the breast beam there extends the shipper stand 2. Rising from the transverse or rock shaft, which extends transversely of the loom as usual, is the arm 3 to which is pivotally connected at 4 the actuator 5 having at its rear end portion a pivotal supported finger 6 adapted at times to be engaged by an operating member 7 which as shown may be formed as part of or connected to the cam follower. The finger 6 is pivotally connected to the actuator 5 at 8 and has a projection 9 which overlies an arm 10 of a bell crank lever pivoted at 11 to a bracket 12 connected to the loom frame or shipper stand. The other arm 13 of the bell crank lever is connected to a transmitter 14 which is associated with a slotted slide 15 mounted in the guideway 16 at the rear portion of the feeler stand 17.

The feeler 18 is shown as of the inclined type, but so far as the present invention is concerned the feeler may be of any desired character. The forwardly extending stem 19 of the feeler passes through a swivel block 20 mounted on the feeler stand.

The feeler 18 is provided with a tooth or projection 21 which is adapted to be engaged by a detent or pawl 22 pivotally mounted at 23 on a bracket 24 which may be conveniently supported by the feeler stand, and the forwardly extending end portion of the detent or pawl 22 is under the influence of a

spring 25, the construction being such that should the feeler be moved frontwardly by a working supply of filling on a detecting beat, the tooth or projection 21 will pass 5 frontwardly of the detent or fall 22 and will be held in its frontward position during the periods of inactivity of the feeler. While any desired character of feeler may be employed with the present invention to be hereinafter 10 described, the mechanism so far set forth is shown as substantially the same as that in the patent to Edward S. Stimpson No. 1,541,755, dated June 9, 1925.

The lay 26 has the usual shuttle box the 15 front wall of which is provided with a slot 27 which registers with a corresponding slot in the front wall of the shuttle when the latter is properly boxed, substantially as set forth in the Stimpson patent above mentioned.

The cam follower 28 may also be of usual 20 construction and the rearwardly extending leg 29 thereof carries a shoe 30 which rides upon a cam 31 mounted on the cam shaft 32 as usual, the construction being such that during rotation of the cam shaft the cam follower will be actuated to carry its upwardly extending portion 28 towards and from the front of the loom, it being understood that the cam follower is pivotally supported as is now common in loom constructions.

The present invention contemplates that the cam follower shall be provided with 35 a periodically actuated mechanism associated with means between the feeler mechanism and the cam follower to free the feeler at intervals, and as one good form of such mechanism it comprises a step-by-step means 40 actuated through the movement of the cam follower. The periodically acting trip mechanism is self-contained; that is it comprises a step-by-step device carried by its own support and adapted to be attached to 45 any of the usual cam followers now common in looms.

In the present instance the step-by-step mechanism comprises a bracket or plate 33 having a laterally extending lug 34 by which 50 the bracket or plate may be secured to the cam follower by means of a bolt or other securing means 35, and in order that the self-contained step-by-step mechanism may be adjusted laterally relative to the cam follower the lug 34 is provided with an elongated slot 36 through which the securing bolt 35 passes for securing the step-by-step mechanism to the cam follower.

Mounted on the bracket or plate 33 is a 60 ratchet wheel 37 which may be conveniently supported upon a pin or dead shaft 38 carried by the bracket or plate, and mounted on the hub portion 39 of the ratchet wheel is a trip lug 40 which, as the ratchet wheel 65 is turned step-by-step, as will hereinafter be

described, acts upon a train of mechanism to trip or free the feeler to the performance of its feeling function.

Pivotaly supported at 41 upon the bracket or plate 33 is a pawl carrier 42 having associated therewith a ratchet actuating pawl 43, and the pawl carrier 42 is normally under the influence of a spring 44 tending to move the pawl carrier and pawl in their idle stroke in a frontward direction. In 70 order that the pawl carrier may be confined to a predetermined range of movement and thereby prevent the pawl 43 from dropping too far in a downward direction, the bracket or plate 33 is provided with a stop shoulder 80 45 adapted to be engaged by an upwardly projecting portion 45 mounted on the pawl carrier. To prevent retrograde movement of the ratchet wheel 37 a check pawl 47 may be provided to engage the tooth of the ratchet 85 and hold it as the pawl carrier and pawl 43 move in the idle stroke. The check pawl 47 is shown as pivotally supported at 48 on the bracket or plate 33.

Since the cam follower has a one-to-two movement relative to the usual crank shaft, a bunter is provided for actuating the pawl carrier 42 as the cam follower is moved under the actuation of its operating mechanism 90 31. In the present instance of the invention the loom frame has secured thereto an arm 49 (Fig. 1) to which is adjustably connected a bunter 50, such adjustable feature of the bunter being provided by means of a slot 51 in the bunter through which passes the 100 securing bolt 52, the construction being such that the bunter 50 may be readily adjusted to impart to the pawl carrier 42 its active stroke as the cam follower moves frontwardly, and such active stroke of the pawl 105 carrier may be regulated to effect a step-by-step movement of the ratchet wheel 37 to the extent of one or more teeth.

Pivotaly mounted at 53 on the bracket or plate 33 is a trip arm 54 having a toe portion 55 adapted to be engaged at times by the trip lug 40, as more clearly indicated in Fig. 2. The trip arm 54 rests upon the end of a plunger 56 carried by a casing 57 secured to the bracket or plate 33, and the opposite end 58 of the plunger rests against the end of a flexible wire 59 enclosed by a flexible sheath 60, the construction being such that when the plunger 56 is pressed against the end of the flexible wire 59 it will move the 115 latter longitudinally in its sheath and such movement is utilized to trip the feeler or free it to its feeling function.

The sheathed wire extends to a bracket 61 which may be conveniently mounted upon the bracket 24 secured to the feeler stand, as indicated in Fig. 1, and the end of the flexible wire 59 at this point rests under a lug 62 carried by the detent or pawl 22, the result 120 being that when the flexible wire 59 is 125 130

5 moved by the plunger 56 it will lift the detent or pawl 22 against the action of the spring 25 and free the feeler to its feeling function, under the action of the usual feeler

5 spring 63.

Since the step-by-step mechanism is self-contained and mounted upon the cam follower, it may be desirable at times that a cover plate 64 be secured to the bracket or

10 plate 33 in overlying relation with the step-by-step mechanism, and this is done in the present instance of the invention by providing bearing lugs 65 and 66 on the bracket or

15 plate 33 or the cover plate 60 respectively, as indicated in Fig. 3, suitable bolts 67 being provided to hold the bracket or plate 33 and the cover plate in their associated relation. Where a cover plate 64 is employed the projecting toe portion 68 of the pawl carrier 42

20 extends beyond the front edge portions of the bracket or plate 33 and the cover plate 64 for engagement by the bunter 50 as the cam follower moves frontwardly. As an additional means for holding the cover plate 25 in its associated relation with the bracket or plate 33 the stud or dead shaft 38 may extend through the cover plate 64 and be provided with a nut 69.

The step-by-step mechanism may be bodily attached to or detached from the cam follower by disengagement of the bolt 35 from the cam follower, a construction which readily adapts the present invention for application to looms now in use.

35 During weaving and as the cam follower moves frontwardly the bunter 50 will actuate the pawl carrier 42 and move the ratchet wheel 37 in its step-by-step movement, and when the trip lug 40 engages the trip arm 54

40 during the step-by-step movement of the ratchet, the plunger 56 will be moved to effect movement of the flexible wire 59 in its sheath, thereby freeing the feeler momentarily so that it may move to its feeling position and then the spring 25 which acts upon the detent or pawl 42 will return the flexible wire 59 to its original position after

45 the trip lug 40 has passed out of engagement with the trip arm. Thus the feeler has periods of activity alternating with periods of inactivity during weaving, and when the feeler detects substantial exhaustion of the filling on a detecting beat during an active period of the feeler, it will call for a change

50 of filling.

55 Claims—

1. In a loom, the combination of the lay, a cam follower, a feeler to detect the condition of the filling in the shuttle, a device for holding the feeler in a frontward inoperative position, a step-by-step mechanism mounted on the cam follower between the lay and loom front for freeing the feeler from said device at intervals and a bunter for actuating said

2. In a loom, the combination of the lay, a cam follower, a feeler to detect the condition of the filling in the shuttle, a device for holding the feeler in a frontward position, a step-by-step mechanism mounted on the cam follower between the lay and loom front, and means for actuating said step-by-step mechanism to free the feeler at intervals during weaving.

3. In a loom, the combination of the lay, a cam follower, a feeler to detect the condition of the filling in the shuttle, a device for holding the feeler in a frontward position, a trip for said device, and a ratchet and pawl mechanism mounted on the cam follower between the lay and loom front for operating the trip to free the feeler at intervals.

4. In a loom, the combination of a cam follower, a feeler to detect the condition of the filling in the shuttle, a device for holding the feeler in a frontward position, a step-by-step mechanism mounted on the cam follower below the operating head or hammer for freeing the feeler from said device at intervals, and a bunter for actuating the step-by-step mechanism on the cam follower.

5. In a loom, the combination of a cam follower, a feeler for detecting the filling in the shuttle, a ratchet and pawl mechanism mounted for bodily movement with the cam follower towards and from the front of the loom, a trip lug carried by said mechanism, means for actuating said mechanism on each movement of the cam follower, a device for holding the feeler in a frontward position, and a trip actuated by the trip lug at intervals to free the feeler.

6. In a loom, the combination of the lay, a cam follower, a feeler to detect the condition of the filling, a device for holding the feeler in a frontward inoperative position, a self-contained trip mechanism movable with the cam follower between the lay and loom front, means for actuating the trip mechanism on the cam follower, and means operated by the trip mechanism for freeing the feeler at intervals.

7. In a loom, the combination of a cam follower, a feeler to detect the condition of the filling, a holding device for holding the feeler in an inoperative position, a trip mechanism mounted on the cam follower between the lay and breast beam, a device for operating the trip mechanism as the cam follower is moved, and means actuated by the trip mechanism at intervals to free the feeler from the holding device.

8. In a loom, the combination of a cam follower, a feeler, a bracket or plate detachably connected to the cam follower, a trip mechanism carried by said plate, means for actuating the trip mechanism on the cam follower step by step, a device for holding the feeler in an inoperative position, and means operated by the trip mechanism for

- freeing the feeler from said device at intervals.
9. In a loom, the combination of the lay, a cam follower, a feeler, a device for holding the feeler in a frontward position, a step-by-step trip mechanism carried by the cam follower between the lay and breast beam, a bunter for actuating said mechanism as the cam follower is moved, and means actuated by the trip mechanism after a plurality of movements of the cam follower for freeing the feeler from said device.
10. In a loom, the combination of a cam follower, a feeler, a device for holding the feeler in an inoperative position, a trip mechanism movable with the cam follower and including a ratchet wheel, a bunter for actuating the ratchet wheel as the cam follower is moved, and means operated by the trip mechanism for freeing the feeler at intervals.
11. In a loom, the combination of a cam follower, a feeler, a device for holding the feeler in an inoperative position, a ratchet wheel mounted on the cam follower and having a trip lug, means for operating the ratchet wheel, and means operated after a predetermined movement of the ratchet wheel to free the feeler from said device.
12. In a loom, the combination of a cam follower, a feeler, a device for holding the feeler in an inoperative position, a ratchet wheel mounted on the cam follower and having a trip lug, a pawl for operating the

ratchet wheel, a bunter for operating the pawl, and means actuated by the trip lug for freeing the feeler at intervals.

13. In a loom, the combination of a cam follower, a feeler, a device for holding the feeler in an inoperative position, a trip mechanism mounted on the cam follower, connections between said trip mechanism and said device including a sheathed wire for freeing the feeler from said device at intervals.

14. In a loom, the combination of a cam follower, a feeler, a device for holding the feeler in an inoperative position, a ratchet wheel having a trip lug and operating pawl movable with the cam follower, a bunter for operating the pawl, and means actuated by the trip lug for freeing the feeler at intervals.

15. In a loom, the combination of a cam follower, a feeler, a device for holding the feeler in a frontward inoperative position, a self-contained trip mechanism carried by the cam follower including a bracket or plate detachably connected to the cam follower, a ratchet having a trip lug and operating pawl mounted on the bracket or plate, means for actuating the pawl, and means operated by the trip lug for freeing the feeler from said device at intervals.

In testimony whereof, I have signed my name to this specification.

HARRY A. DAVIS.
